United States Patent Office

Des. 221,640
Patented Aug. 31, 1971

221,640

WHEEL

Paul W. Burchard, 415 Rialto Ave.,
Rialto, Calif. 92376

Filed June 30, 1970, Ser. No. 23,768

Term of patent 3½ years

Int. Cl. D12—14

U.S. Cl. D14—30

FIG. 1.

FIG. 3.

FIG. 2.

FIG. 4.

FIG. 5.

FIG. 1 is a three-quarter front perspective view of a wheel embodying my new design;

FIG. 2 is a front elevation of the same;

FIG. 3 is a side elevation;

FIG. 4 is a rear elevation; and

FIG. 5 is a vertical sectional view.

I claim:

The ornamental design for a wheel, as shown.
